ABSTRACT OF THE DISCLOSURE

An explosive composition is formed by mixing together a particulate inorganic oxidizer, a substantially saturated aqueous solution of magnesium nitrate, ammonium nitrate, or an aqueous ammoniacal ammonium nitrate solution, a setting agent which sets said composition to a solid material and a small but effective amount of a polymeric organic latex to increase the physical strength of said explosive and permitting the mixture to set. Chlorine containing organic polymeric latexes also increase the sensitivity of the explosive composition.

BACKGROUND OF THE INVENTION

In U.S. Pat. 3,326,734 an explosive composition is taught and claimed comprising a particulate inorganic oxidizer, a substantially saturated solution selected from the group consisting of aqueous magnesium nitrate, aqueous ammonium nitrate and aqueous ammoniacal ammonium nitrate, and a setting agent which sets the explosive composition to a solid material containing solvent used in a liquid phase. The setting agent comprises certain inorganic oxides or salts. Other constituents that can be included are other fuel components such as particulate metals, organic materials such as alcohols, urea and the like. The present invention concerns an improvement in the composition disclosed in said patent No. 3,326,734. All the teachings of U.S. Pat. 3,326,734 are specifically incorporated herein by reference.

The present invention comprises adding to the composition of U.S. Pat. 3,326,734, during the manufacture thereof, a small but effective amount of a polymeric organic latex prior to the setting of said composition. Organic polymeric latexes which can be employed include, for example, various vinylidene chloride latexes. Preferred latexes are those taught in U.S. Pat. 3,411,943. The teachings found at column 1, line 44 through column 2, line 31 of said patent are specifically incorporated herein by reference. Other organic polymeric latexes can be employed. Organic polymeric latex materials containing chlorine atoms in the polymer tend to, in addition to increasing the physical strength, increase the sensitivity of the explosive composition, i.e., decrease the critical diameter of the explosive.

Polymeric organic latex is employed in an amount rang-

2

ing from about .1 to about 10% (based on the weight of the solids present in the latex) by weight of the explosive composition disclosed in U.S. Pat. 3,326,734.

The explosive composition of the invention is prepared in the following manner. The solid particulate oxidizer is blended with the setting agent, e.g. magnesium oxide and other solid components if used, e.g. particulate metals and the like and the saturated nitrate solution, and any other liquid component then added to this mixture. Preferably the latex is added last and the mix cast into molds immediately thereafter before the latex coagulates and salts out.

As an example a composition of the present invention is prepared in the following manner. Particulate magnesium/aluminum alloy (50/50 by weight), 1053 grams is added to a mixing container. The particulate metal has a size distribution between —20 and +325 mesh U.S. Standard Sieve Series. To the particulate metal is added 982 grams of a fuel solution containing as parts by weight 50 ammonium nitrate, 21 H₂O and 31 beet sugar. To this mix is then added 750 grams of fine ground ammonium nitrate with mixing. Following this 210 grams of magnesium oxide is thoroughly mixed therein followed by 753 grams of additional fine ground ammonium nitrate. Finally 80 grams of a 50 percent solids latex of a polymer of 75 parts by weight vinylidene chloride, 25 parts chloride, 3 parts ethyl acrylate and 2 parts methyl methacrylate is thoroughly mixed with the other constituents and the composition is cast into a mold where it sets up to form a hard set mass.

EXAMPLE

Various compositions were prepared according to the procedure taught in U.S. Pat. 3,326,734. To certain of the compositions was added a latex comprising 50% by weight of an organic polymeric material comprising a polymer of 25 parts vinyl chloride, 75 parts vinylidene chloride, 3 parts ethyl acrylate, 2 parts methyl methacrylate and 50% by weight H₂O. Certain of the compositions were tested in a standard lead block deformation test, said test being well-known in the art and being described at column 4, lines 1–18 of U.S. Pat. 3,326,734.

Certain of the compositions were shot in a 2 inch diameter by 12 inch long tube, and the amount of material remaining following the shot was measured. This test is employed to compare the relative sensitivity (i.e. ability to sustain propagation) of various compositions. In these tests the compositions were all detonated employing a 40 gram high pressure booster. The temperature of the explosive at the time of detonation was about 70° F.

Certain of the other compositions were cast into the 7 inch diameter spheres and the physical characteristics thereof (i.e. strength) determined.

The compositions and the results of the various tests performed thereon are set forth in the following table.

TABLE

Test type	Test No.	Parts by weight				Density control agent	Sulfur	Thio-urea	Latex	Density, gm./cc.	ΔH , inches	Teft in tube, inches	Physical characteristics
		AN	MgO	Metal ¹	Fuel solution ²								
Lead block	1	85.6	12	60	56	1			3	1.05	1.06		
Do	2	85.6	12	60	56				3	1.18	1.01		
Do	3	86.6	12	60	56				6	1.16	0.63		
Do	4	86.6	12	60	56	1			9	1.13	0.12		
Do	5	85.6	12	60	56	1			12	1.12	0.03		
Do	6	1,503	211	1,053	983	90	60			1.04	.98		
Case into 7" diameter sphere.	7	1,503	211	1,053	986	90	60			0.92		Poor physical strength.	
Do	8	1,503	210	1,053	982		60		80	0.92		Excellent physical strength.	
2" x 12" tube	9	300	42	210	196		7		10.5	1.11	5.25		
Do	10	330	46.2	231	215		2		12	1.23	7.25		
Do	11	564	79.2	3462	369.6		66		20	1.11	5.5		
Do	12	300	42	4245	196		4		11	1.11	6.6		
Do	13	1,503	211	1,053	986	90	60			1.03	2.0	Poor physical strength.	
Do	14	1,503	210	1,053	982		60		80	1.11	6.5	Excellent physical strength.	

¹ Particulate metal comprised a 50:50 part by weight Mg-Al alloy having particles between 20+325 mesh, U.S. Standard Sieve.² Fuel solution comprises as parts by weight, 50 NH₄NO₃, 21 H₂O, 31 beet sugar.³ Metal comprised 396 parts of the 50:50 Mg-Al alloy and 66 parts flake Al.⁴ Metal comprised 210 parts of the 50:50 Mg-Al alloy and 35 parts flake Al.

What is claimed is:

1. An explosive composition comprising:

- (a) from about 40 to about 75 parts by weight particulate ammonium nitrate;
- (b) from about 20 to about 35 parts by weight of a solution selected from the group consisting of aqueous magnesium nitrate, aqueous ammonium nitrate and aqueous ammoniacal ammonium nitrate;
- (c) at least about 2 parts by weight of a setting agent selected from the group consisting of alkaline earth metal oxide, zinc oxide, lead monoxide, calcined dolomitic limestone, substantially anhydrous calcium sulfate, substantially anhydrous magnesium sulfate, substantially anhydrous sodium tetracyanophosphate and substantially anhydrous sodium thiosulfate, said member being further characterized as setting said composition to a solid material which contains solvent used in the liquid phase; and
- (d) an effective amount of a vinylidene chloride organic polymeric latex to increase the strength of said set explosive composition.

2. The composition of claim 1 wherein said latex comprises, a percent by weight of solids in said latex, from about 0.1 to about 0.1 to about 10 percent of said explosive composition.

3. The composition as defined in claim 2 wherein the setting agent is an alkaline earth metal oxide and is characterized in that it reacts with the solvent of the nitrate solution over a period of time and sets said composition to a solid containing said solvent member.

4. The explosive composition as defined in claim 3 wherein the setting agent is magnesium oxide.

5. The explosive composition as defined in claim 3 and having up to about 50 parts by weight of a particulated light metal.

6. The explosive composition as defined in claim 2 which comprises:

- (a) from about 50 to about 70 parts by weight prilled ammonium nitrate;
- (b) from about 22 to about 28 parts by weight of a substantially saturated solution selected from the group consisting of aqueous magnesium nitrate, aqueous ammonium nitrate and aqueous ammoniacal ammonium nitrate, and
- (c) from about 4 to about 8 parts by weight magnesium oxide to effect solidification of said composition.

7. The explosive composition as defined in claim 6 and having from about 2 to about 25 parts by weight of particulated aluminum.

8. The composition of claim 2 wherein said latex con-

sists of a thermoplastic vinylidene chloride interpolymeric latex consisting essentially of from about 35 to about 90% by weight of vinylidene chloride and from about 65 to about 10% by weight of a dissimilar interpolymerizable comonomer, as based on a total interpolymeric latex solids content of 100% by weight.

9. A method for preparing a dense, water-resistant inorganic based explosive composition which comprises:

- (a) blending from about 40 to about 75 parts by weight solid particulate ammonium nitrate with at least about 2 parts by weight of a member selected from the group consisting of alkaline earth metal oxides, zinc oxide, lead monoxide, calcined dolomitic limestone, substantially anhydrous calcium sulfate, substantially anhydrous magnesium sulfate, substantially anhydrous sodium tetracyanophosphate and substantially anhydrous sodium thiosulfate, said member being further characterized in setting said composition to a solid material which contains solvent used in the liquid phase of a solution selected from the group consisting of aqueous magnesium nitrate, aqueous ammonium nitrate and aqueous ammoniacal ammonium nitrate;
- (b) adding to the resulting blend from about 20 to about 35 parts by weight of a solution selected from the group consisting of aqueous magnesium nitrate, aqueous ammonium nitrate and aqueous ammoniacal ammonium nitrate;
- (c) mixing the liquid and solid components to provide a substantially homogeneous composition;
- (d) blending with said homogeneous composition an effective amount of a vinylidene chloride organic polymeric latex to increase the strength of said set explosive composition; and
- (e) curing said composition to provide a dense, set, water-resistant explosive composition.

10. The process as defined in claim 9 employing from about 50 to about 70 parts by weight particulate ammonium nitrate and from about 4 to about 8 parts by weight magnesium oxide to provide the initial blend of solids and having from about 22 to about 28 parts by weight of a substantially saturated solution selected from the group consisting of aqueous magnesium nitrate, aqueous ammonium nitrate and aqueous ammoniacal ammonium nitrate mixed therewith and from about 0.1 to about 10%, based on the weight of solids in said latex, of said latex.

11. The process as defined in claim 9 and including the step of incorporating up to about 50 parts by weight of a particulated light metal into the initial blend of solids.

12. The method as defined in claim 9 wherein said latex is provided in an amount based on the solids present in said latex, ranging from about 0.1 to about 10% by weight of said composition.

13. The method of claim 12 wherein said latex consists essentially of from about 35 to about 90% by weight of vinylidene chloride and from about 65 to about 10% by weight of a dissimilar interpolymerizable comonomer, as based on a total interpolymeric latex solids content of 100% by weight.
